SHOWER CURTAIN HOOK

Heinz Nathanson, 160 5th Ave.,
New York, N.Y. 10010

Filed May 16, 1969, Ser. No. 17,179

Term of patent 14 years

Int. Cl. D8—03

U.S. Cl. D8—248

FIG. 1 is a front perspective view of a shower curtain hook, showing my new design.

FIG. 2 is a side elevational view.

FIG. 3 is a front view.

FIG. 4 is a rear view thereof.

I claim:

The ornamental design for a shower curtain hook, substantially as shown.
